UNITED STATES PATENT OFFICE.

LEWIS S. WATRES, OF SCRANTON, PENNSYLVANIA, ASSIGNOR TO NATIONAL GRAPHITE LUBRICATION COMPANY, OF WILMINGTON, DELAWARE, A CORPORATION OF DELAWARE.

APPARATUS FOR ABRADING GRAPHITE OR SIMILAR MATERIAL.

Original application filed July 11, 1924, Serial No. 725,377. Divided and this application filed December 5, 1925. Serial No. 73 310.

This invention is a division of my application Serial No. 725,377, filed July 11, 1924, and relates to apparatus for effectively abrading solid material such, for example, as graphite, and introducing the same in regulated amounts into regions where it may perform a desired function.

In my prior Patent, No. 1,189,643, of July 4, 1916, I have described and claimed one form 10 of apparatus for abrading graphite in the form of sticks, such apparatus being shown in conjunction with a locomotive boiler and arranged so as to introduce the graphite in finely divided form into the conduit supplying 15 saturated steam to the superheater. My invention is an improvement over that described in said patent and while particularly adapted for use in connection with the saturated steam conduit of a locomotive, may be 20 used for other purposes, and particularly for the lubrication of various moving parts either in a railway motor or other oscillating support.

The accompanying drawings illustrate a 25 number of forms of my improved device. Fig. 1 is a perspective view with parts broken away of a locomotive boiler with a device of my invention installed; Fig. 2 is an enlarged view of an embodiment of my invention, the 30 cover-plate having been removed; Fig. 3 is a view mainly in vertical section of the construction shown in Fig. 2; Fig. 4 is an elevational view of a modification; and Fig. 5 is a view along lines 5-5 of Fig. 4.

Referring to said drawings, 10 denotes a chamber casing having a stem 11 provided with a bore 11^a therethrough, and having a valve 12, to which is threaded a pipe 13 which may extend, when the device is mounted for 40 use, through a locomotive boiler shell 14, and into the saturated steam conduit 15 shortly before the steam enters the manifold or header 16 for the superheater tubes 17.

A threaded stud 18 is preferably provided, 45 by means of which casing 10 may be braced to the boiler shell 14. Mounted in casing 10 is an oscillating member consisting of a comparatively heavy plate 40, the upper surface of which carries the abrasive material 41 such 50 as crystals of silicon carbide, the underside being smooth and engaging rollers 42, having as bearings studs 43, 43 projecting from the casing 10. The ends of the plate 40 may be

provided with springs 44 which strike against opposite sides of the casing 10 and cause plate 55 40 to rebound therefrom. Casing 10 has a cover 24 which is clamped in place by means of bolts through holes in ears 25 provided around the casing 10.

For the purpose of feeding solid material, 60 such as graphite sticks onto the abrasive surface 41, I have provided a magazine 27 which is held in place by means of a collar portion 28 resting upon a shoulder 29 in the body of the chamber casing. A cap 30 engages in threaded 65 relationship an annular extension 31 of casing 10, and is provided with an internal lug 32 which bears down upon the top of the collar portion 28 and holds it firmly against shoulder 29 whereby the tube 27 is held rigidly in place. I preferably provide a hole 70 27^a in tube 27 to insure equalization of pressure within the magazine. As the material to be abraded I prefer to use sticks 33 of compacted, flocculated graphite as made in accordance with the patent to George Kirkegaard, No. 1,185,682, of June 6, 1916.

In use my improved device may be mounted 75 on a locomotive boiler, as shown in Fig. 1, being placed with the oscillator at right-angles to the longitudinal axis of the boiler. Before starting a run a number of the graphite sticks are placed in the magazine 27, valve 12 being of course shut off. Due to the lateral vibration or "nozing" of the locomotive, the 80 oscillator will be kept in constant motion and will continue to abrade particles of the graphite sticks by the action of abrasive surface 41. Valve 12 being open, the particles produced by the abrasion of the graphite will find their 85 way through bore 11^a into the stream of saturated steam on its way to the superheater, the presence of the graphite particles serving the dual purpose of effectively stopping up in their incipiency leaks in the couplings or 90 joints of the superheater and lubricating the valves and pistons of the locomotive, all as more fully described in my aforementioned Patent, No. 1,189,643.

It will be noted that while there is no direct 100 circulation of steam through the casing 10, that there is a continual surging of the steam due to the action of cylinders. In addition a more or less diminished pressure results in 105 casing 10 whenever the steam is cut off by means of throttle 34, while when the throt-

tle is open full boiler pressure is immediately built up in said casing. Due to both these causes, the particles of the graphite are effectively carried out of casing 10.

5. In Figs. 4 and 5 a ball 50 travels on a support 51, and strikes against the depending legs or stops 52, 52 of plate 53 having an abrading surface 54, and thus serves to move said plate back and forth and cause it to oscillate longitudinally as it slides on the ledges 54.

The amount of graphite consumed will depend somewhat upon the weight of the material above the surface undergoing abrasion, 15 and the rate of consumption can therefore be to some extent controlled.

It will be seen from the foregoing that I have provided a simple though exceedingly effective device for abrading and feeding 20 graphite into the saturated steam conduit of a locomotive or in any region thereof in which it might be desirable to admit such granular material. Furthermore, my device requires no external power means for its operation. It will also be apparent that various changes may be made in the detailed construction of my device, for which reason I do not intend to limit my invention to such constructional details. For example, the oscillator member may be used to operate a separate abrading means in various ways which 25 will occur to the skilled mechanic.

I claim:

1. In combination a vibrating support, a 35 chamber mounted thereon, a magazine tube extending into said chamber, an outlet from

said tube into said chamber, abrasive material in said chamber, a rectilinear moving oscillator operated by the vibration of said chamber, said abrasive material being carried by 40 said oscillator.

2. An abrading apparatus adapted to be mounted upon a railway motor and comprising in combination a chamber, a magazine tube extending thereinto, an outlet from said tube, a rectilinear moving oscillator operated by the vibration of said chamber, an abrasive surface carried by said oscillator, said outlet being positioned so as to permit the feeding of material to be abraded upon said abrasive 45 surface.

3. In combination, a vehicle, a chamber mounted thereon, abrasive material, a plate oscillator longitudinally operated by transverse motion of said vehicle, said abrasive 50 material being carried by said oscillator.

4. In combination, a vehicle, a chamber mounted thereon, abrasive material, a plate oscillator longitudinally operated by transverse motion of said vehicle, said abrasive 55 material being carried by said oscillator, and means independent of said plate to aid its oscillation by impact.

5. In combination, a vehicle, a chamber mounted thereon, abrasive material, a plate oscillator longitudinally operated by transverse motion of said vehicle, said abrasive 60 material being carried by said oscillator and a ball within said chamber to aid the oscillation of said plate.

LEWIS S. WATRES.
